LINER FOR CRUSHERS

Rudolph J. Gasparac, Milwaukee, and Arnold P. Szaj, Hales Corners, Wis., assignors to Nordberg Manufacturing Company, Milwaukee, Wis., a corporation of Wisconsin

Filed Oct. 21, 1965, Ser. No. 499,427
5 Claims. (Cl. 241—299)

ABSTRACT OF THE DISCLOSURE

The invention relates to an improvement in bowl liners for crushers in which helical wedge receiving surfaces are employed, adjacent surfaces being helically disposed in opposite directions, whereby to provide a self-locking effect in response to the rotation of the bowl liner in either direction.

This invention is in the field of material reduction machines and is concerned, among other things, with an improved crusher with a gyrated head. A primary object is to provide an improved bowl liner for such crushers.

Another object is to provide an improved locking arrangement for such bowl liners.

Other purposes will appear from time to time in the course of the specification and claims.

The invention is illustrated more or less diagrammatically in the accompanying drawings wherein:

FIGURE 1 is a partial, vertical, radial section through a crusher illustrating the invention;

FIGURE 2 is a side elevation, on a smaller scale, of the bowl liner;

FIGURE 3 is a plan view of the liner shown in FIGURE 2;

FIGURE 4 is a partial side elevation, on an enlarged scale, of the structure of FIGURE 3, as illustrated at 4—4 in that figure;

FIGURE 5 is a section, on an enlarged scale, on the line 5—5 of FIGURE 3; and

FIGURE 6 is a section, on an enlarged scale, on the line 6—6 of FIGURE 3.

Like parts are indicated by like symbols throughout the specification and drawings.

Referring to the drawings, FIGURE 1 illustrates parts of a crusher structure, the details of the crusher as a whole not forming part of the present invention. The present application is an improvement on the structure shown in copending application Ser. No. 228,533, filed in the United States Patent Office on Oct. 5, 1962, in the name of Loren G. Symons, which issued on Feb. 15, 1966 as Patent No. 3,235,190. It will be understood that the type of crusher with which the present invention is used includes a circumferential main frame, not herein shown, a tilting ring mounted on the upper edge of the main frame, to provide an overload release, and a bowl adjustable on the tilting ring. The bowl is indicated in section in FIGURE 1, as 1. It includes the outwardly extending adjusting threads 2. It has an inwardly extending bowl portion having a generally conic lower surface 3 and a generally plane upper annular surface 4, the purpose of which will later appear. For convenience, the bowl has pockets shown at 5. The particular bowl liner herein shown includes a lower, generally conic portion 6 and an upwardly extending, generally cylindrical portion 7 having a circumferential, outwardly extending guide flange or positioning flange 8 and an upper flange 9, the elements of which will later be described. The bowl is shown as including an inner cylindrical surface 10 of a slightly greater diameter than the exterior diameters of the flanges 8 and 9 of the bowl liner. Thus the bowl liner

2

may be upwardly inserted through the aperture defined by the cylindrical face 10. An opposed crushing member, the details of which form no part of the present invention, is gyrated within the bowl. A mantle is indicated, having a generally conic crushing portion 12. It will be understood that by suitable means, not herein shown, a head is gyrated, and carries with it the member 12, moving it toward and away from the liner 6 in order to reduce such particles as are fed from above into the space between the members 6 and 12. The reduced particles escape through the lower, outer gap between the members 6 and 12 and are received for further treatment or transportation by means not herein shown.

A primary purpose of the present invention is to provide an improved wear-taking part for crushers having gyrated heads, the part constituting, preferably, a bowl liner defining the upper or outer surface of the crushing cavity. Another primary purpose of the present invention is to provide improved locking means for such a bowl liner, the locking means being associated with the improved design of the bowl liner, whereby the bowl liner will automatically tighten itself in the course of its use.

In securing the bowl liner 6, 7 in position, it is upwardly inserted through the opening of the cylindrical

surface 10 until it abuts the conic surface 3 of the bowl

1. Similarly, when freed, the bowl structure or bowl liner may be downwardly freely removed through the bowl 1 when removal is desired. Simple means are provided for holding the bowl liner in position without the use of any

complicated structure, and without the use of any securing means which can get so packed with material or dust during use as to cause difficulties in removal. As will be clear from FIGURE 1, the ring 3 includes a generally plane upper surface 4. Wedges 20 rest thereon, and may be thrust inwardly toward and beneath the upper flange 9 of the bowl liner by the use of thrust nuts 21 mounted on bolts or threaded shanks 22, the heads 23 of which are formed to be held in any suitable sockets or apertures or upwardly open slots 24 formed in the bowl 1. Tightening

the thrust nut 21 has an effect to force the wedge 20 to the right, referring to the position of the parts of FIGURE 1. Its wedge surface 20a underlies the flange 9, and its inner end 20b is so proportioned as to avoid movement limiting engagement with the outer surface of the cylindrical portion 7 of the bowl liner.

It will be observed that the outer surface of the flange 9 is composed of a sequence of helical locking surfaces. These surfaces are continuous, the closest approach to the center A of the bowl liner being indicated at X in FIGURE 3, where the section 6—6 is taken, and the most remote part being at Y, where the section 5—5 is taken. It will be observed from FIGURE 3 that each wedge segment is helically divergent from its adjacent wedge segments. Thus, going clockwise about the bowl liner, one wedge surface will extend from Y to X, from a maximum to a minimum diameter, whereas the next wedge surface will extend from a point of minimum diameter to a point of maximum diameter. This sequence continues throughout the circumference of the flange 9.

Likewise, the lower outer surface of the flange 9 is spiraled, as shown in FIGURE 4, to form a series of wedge surfaces extending between points 9a and 9b. The point 9a is indicated also on the section of FIGURE 5, and the point 9b on the section of FIGURE 6. In effect, the flange 9 is broken into a series of wedge surfaces which are both helical and spiral, in the sense that, as you advance from 9a to 9b, the outer edge of the flange moves from Y to X, and the lower surface of the flange moves from 9a to 9b. The effect of this combination of helix and spiral will later be discussed in detail. But when the wedges 20 are thrust inwardly against the abutting sur-

faces of the flange 9, the result of the formation of the flange is to provide a self-locking effect.

In use the wedges 20 may be differentially forced in against the locking surfaces formed about the outer edge of the flange 9. They are forced in by rotation of the thrust nuts 21 until the bowl liner 6, 7 is pulled firmly upwardly against the lower bowl surface 3. The direction of the helix engaged by each wedge is such that the liner tends to tighten itself on the faces of the wedges. The upper or reinforcing or locking flange 9 is continuous, and has an outwardly, generally continuous lower surface, the nature of the contact between the wedges and the helices and spirals rendering the liner self-tightening. Each of the surfaces, such as the one extending from X to Y in FIGURE 3, or from 9b to 9a in FIGURE 4, is both eccentrically and helically disposed relative to the axis of the crusher. The point of maximum downward helical excursion, as at 9a, lies within the circumferential interior of the supporting surface 4, or of the cylindrical surface 10, when the liner is properly positioned at the bowl. The point of maximum outward eccentric excursion, as at Y, lies within the circumferential interior of the supporting surface, so that the liner is easily inserted and removed.

The effect of this combination of the helically and eccentrically disposed surface is that the reactive thrust against the wedge face 20a is at a distinct angle, such as along the broken line indicated at Z in FIGURE 1. This has the advantage that the line of reaction will fall outside of the inner edge of the supporting surface 10. This is to say that the reaction will fall on the supporting surface, as indicated by the broken line.

Since the flange 9 is bounded by a series of spirals and helices, which are "inclined" to each other, the operation is the same regardless of whether or not the bowl liner may tend to rotate or creep clockwise or counter-clockwise. In either event, there is a series of spiraled and helical surfaces against which the wedges 20 thrust.

It will be realized that whereas we have shown a practical and operative device, and a practical form of bowl liner, nevertheless many changes may be made in size, shape, number and disposition of parts. Thus the shape and the location of the crushing surfaces of the bowl liner 6, 7 may be widely varied. Likewise, there are permissible variations in the formation of the wedge surfaces, and in the shape of the flange 9, and in the details of the bowl structure with which the bowl liner is used. We wish our description and drawings to be taken, therefore, as in a broad sense illustrative or diagrammatic.

We claim:

1. In a bowl liner for gyratory crushers and the like, a generally frusto-conic body having about its upper edge an outwardly extending continuous flange adapted to receive locking wedges, the lower outer surface of said flange being formed into a plurality of wedge receiving surfaces, each of which is eccentrically and helically disposed relative to the liner axis such that the liner will tend to be self-tightening on the bowl, the surfaces being arranged in a continuous series throughout the flange, each such surface being eccentric in relation to the adjacent surfaces, adjacent surfaces being helically disposed in opposite directions, whereby to provide oppositely effective wedge receiving surfaces, at either direction of rotation of the liner in the course of its use.

2. In a bowl liner for gyratory crushers and the like, a generally frusto-conic body having about its upper edge an outwardly extending continuous flange adapted to receive locking wedges, the lower, outer surface of said flange being formed into a plurality of wedge receiving surfaces each of which is eccentrically and helically dis-

posed relative to the liner axis, whereby the liner will tend to be self-tightening on the bowl, the outer, lower surface of the flange defining a continuous series of such eccentrically and helically disposed surfaces, each such surface differing from the adjacent surfaces in its eccentricity and its spiral pitch, adjacent surfaces being helically disposed in opposite directions whereby to provide adjacent, oppositely effective wedge receiving surfaces, at either direction of rotation of the liner in the course of its use.

3. In a bowl liner for gyratory crushers and like, a generally frusto-conic body having about its edge an outwardly extending flange, continuous about its circumference, adapted to receive locking wedges, the lower outer surface of the flange being formed into a plurality of surfaces each of which is eccentrically and helically disposed relative to the liner axis such that the liner will tend to be self-tightening on the bowl, the surfaces being arranged in a uniform and continuous series throughout the flange, each such surface being eccentric in relation to the adjacent surfaces, the adjacent surfaces being helically disposed in opposite directions, whereby to provide oppositely effective wedge receiving surfaces adapted to cooperate with each wedge employed at either direction of rotation of the liner in the course of its use.

4. A bowl liner for use in gyratory crushers and the like, with means for supporting and securing the liner in relation to the bowl support with the crusher having a supporting, upwardly facing annular surface about the upper end of the bowl liner, the improvement comprising a generally frusto-conic metal body adapted to be disposed generally upright in such crusher, small end up, and having an outwardly extending, generally continuous flange about its upper end disposed circumferentially about the upper end of the liner and having a generally continuous lower surface, the liner being constructed so that when it is properly positioned in the crusher the lower surface of the flange will be at a level slightly above the supporting surface of the crusher, the lower surface of the flange being divided into a series of separate lock receiving surfaces, each of the separate surfaces increasing helically in excursion in a direction such that the liner will tend to be self-tightening in use, adjacent surfaces being helically disposed in opposite directions, whereby the liner will tend to be self-tightening in use at either direction of rotation of the liner, the maximum helical downward excursion of each such surface lying in a plane generally above the supporting surface of the crusher when the liner is properly positioned in the crusher.

5. In a bowl liner for gyratory crushers and the like, a generally frusto-conic metal body having about its upper edge an outwardly extending continuous flange adapted to receive radially inwardly moving locking members, the lower outer surfaces of the flange being formed into a plurality of receiving surfaces, each of which is helically disposed relative to the liner axis such that the liner will tend to be self-tightening on the bowl, in response to the inward radial movement of locking members, the surfaces being arranged in a continuous series throughout the flange, the adjacent surfaces being helically disposed in opposite directions whereby to provide opposite effective lock-receiving surfaces at either direction of rotation of the liner in the course of its use.
